(57) **CLAIM**

The ornamental design for an enclosure, as shown and described.

DESCRIPTION

FIG. 1 is a left front perspective view of an enclosure according to the present invention;

FIG. 2 is a front view of the enclosure shown in FIG. 1; and, FIG. 3 is a top view of the enclosure shown in FIG. 1.

The broken lines showing other portions of the enclosure in FIGS. 1-3 are for illustrative purposes and form no part of the claimed design.

1 Claim, 3 Drawing Sheets

FIG. 1

FIG. 2

FIG. 3
